Attorneys

UNITED STATES PATENT OFFICE.

JOE HUSZARIK, OF CLEVELAND, OHIO.

SPARK ARRESTER.

Application filed November 18, 1924. Serial No. 750,578.

To all whom it may concern:

Be it known that I, JOE HUSZARIK, a citizen of the United States of America, residing at Cleveland, in the county of Cuyahoga and State of Ohio, have invented certain new and useful Improvements in Spark Arresters, of which the following is a specification.

This invention relates to new and useful improvements in spark arresters.

The primary object of the invention is to provide a device which may be detachably secured to a stack for arresting the sparks discharged therefrom with smoke or other gases.

A further object of the invention is to provide a novel form of mounting for a spark arrester by means of which the latter may be adjustably secured to a stack.

A still further object of the invention is to provide a spark arrester of the above mentioned type which is of exceedingly simple construction and one that may be easily and quickly mounted in place.

Other objects and advantages of the invention will be apparent during the course of the following description.

In the accompanying drawing forming a part of this specification and in which like numerals are employed to designate like parts throughout the same,

Figure 1 is a side elevational view of the spark arrester shown mounted upon a smoke stack, shown in dotted lines;

Figure 2 is a top plan view of the spark arrester shown in Fig. 1;

Figure 3 is a central vertical sectional view of the spark arrester shown in Figs. 1 and 2, and

Figure 4 illustrates a modified form of mounting for the arrester.

In the drawing, wherein for the purpose of illustration is shown a preferred embodiment of this invention, the numeral 5 designates the upper or discharge end of a stack. In Figs. 1 to 3 inclusive, a two-part collar 6 is illustrated as consisting of the parts —a— and —b— which are of substantially semi-circular form and have their opposite ends bent laterally to form the lugs 7 which are apertured for receiving the clamping bolts 8 by means of which the collar may be adjustably secured to the stack 5. Suitably secured to the intermediate portion of each collar part is the foot portion 9 of a substantially U-shaped bracket 10 which

has its upper end bent inwardly to form a supporting lug 11. Clamped between the laterally projecting ends of the collar parts are the foot portions 12 of the arcuate brackets 13 which have their upper ends bent laterally to form the supporting lugs 14.

The spark arrester screen 15 is of disk formation and has its peripheral edge clamped between the superimposed, two part clamping rings 16 and 17 which are formed of the semi-circular part —c— and —d— respectively. It will be noticed that the mating ends of the parts —c— of the ring 16 are arranged at right angles to the mating ends of the parts —d— of the ring 17. The overlapping of these ring parts will materially strengthen the structure just described. These ring parts are bolted together by the fastening means 18 which have the nut locking wires 19 threaded thru suitable openings formed in the bolt portions of the fastening means. These fastening means 18 are also employed for mounting the screen 15 and rings 16 and 17 upon the supporting lugs 11 and 14 of the brackets 10 and 13.

It will be seen that by loosening the clamping bolts 8, the collar 6 may be adjusted longitudinally of the stack 5 for varying the distance between the discharge orifice of the said stack and the screen 15.

In Fig. 4 there is shown a modified form of mounting for the arresting screen 15 which will permit the ready adjustment of the latter to vary its distance from the discharge orifice of the stack 5. In this figure, the numeral 5^a designates the stack which has permanently secured thereto the angle brackets 20 having internally threaded enlargements 21 formed on the outer ends thereof. While only one bracket is shown in this figure, it is to be understood that a suitable number of the same are to be provided and mounted upon the stack 5^a in the manner illustrated. Encircling this stack 5^a is a collar 6^a which is intended to be formed of two parts in the same manner as the collar 6, shown in Figs. 1 to 3 inclusive, but the collar 6^a is to be formed with a diameter greater than the external diameter of the stack 5^a. The collar 6^a is formed of this diameter to permit the same to slide freely upon the stack. The collar 6^a is provided with the same kind of brackets as those designated by the numerals 10 and 13 in Figs. 1 to 3 inclusive. Each

of these brackets of a similar construction to the brackets 10, in the first form, as designated by the numeral 10^a in Fig. 4, is provided with a bearing opening 22 that 5 rotatably receives the upper end 23 of the threaded rod 24. This threaded rod is connected to the bracket 10^a by the rings 24 to prevent the rod from separating from the said bracket. The threaded portion of 10 this rod is mounted within the bore of the enlarged portion 21 of the bracket 20 and engages the threads formed in the same for causing longitudinal movement of the collar 6^a in respect to the stack 5^a when the rod 15 is rotated. The lower end of this rod is provided with a winged head 24 by means of which the said rod may be rotated manually.

It is to be understood that the forms of 20 this invention herewith shown and described are to be taken as preferred examples of the same, and that various changes in the shape, size, and arrangement of parts may be resorted to without departing from the 25 spirit of the invention or the scope of the subjoined claim.

Having thus described the invention, I claim:—

In a spark arrester, a mounting collar 30 formed of two parts with the parts having mating apertured ears for receiving connecting bolts, a U-shaped bracket fastened to each collar part with one side arranged in parallelism with the plane of the collar, an arcuate bracket clamped at its lower end 35 between each pair of mating apertured ears and having lateral lugs at their upper ends, and a spark arrester structure fastened to the upper ends of the U-shaped and arcuate brackets, said spark arrester structure including a disk-shaped screen, and two-part 40 clamping rings overlying and underlying said screen and bolted thereto and to the said brackets, the parts of said rings being of semi-circular shape and arranged in 45 respect to each other with the mating ends of one ring arranged at right angles to the mating ends of the other ring.

In testimony whereof I affix my signature.

JOE HUSZARIK.
